(57) **CLAIM**

The ornamental design for a string fastener, as shown and described.

DESCRIPTION

FIG. 1 is a perspective view of a string fastener showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the portion 8 of FIG. 2.

The broken lines in the drawings illustrate portions of the string fastener and form no part of the claimed design.

1 Claim, 8 Drawing Sheets(56)
